DESIGN FOR A CHILD'S TRAINER OR SIMILAR ARTICLE

James P. Budrakey, Troy, N. Y.

Application August 31, 1945, Serial No. 121,766

Term of patent 14 years

(Cl. D15—8)

To all whom it may concern:

Be it known that I, James P. Budrakey, a citizen of the United States, residing at Troy, county of Rensselaer, and State of New York, have invented a new, original, and ornamental Design for a Child's Trainer or Similar Article, of which the following is a specification, reference being had to the accompanying drawing, forming a part thereof in which

Fig. 1 is a perspective view of a child's trainer or similar article showing my new design; and

Fig. 2 is a rear elevational view of the child's trainer or similar article.

I claim:

The ornamental design for a child's trainer or similar article, as shown.

JAMES P. BUDRAKEY.
